 mesne assignments, to Reconstruction Finance
 Corporation, Chicago, Ill., a corporation

Application August 26, 1935, Serial No. 37,906

7 Claims. (Cl. 205—7)

Our invention relates in general to the manufacture of tubes and has more particular reference to tubes having substantially capillary bore;

An important object of the invention is to 5 provide for drawing a capillary tube having smooth even bore surfaces.

Another object is to provide for drawing a tube over a mandrel of hardened steel having a chromium plated drawing surface so that the 10 product has a smooth bore surface of uniform diameter and cross-sectional shape throughout its length.

Another object is to provide for drawing a tube through a die and over a chromium plated 15 mandrel; a further object being to utilize a chromium plated carboloy or other like hard metal die for drawing tubing.

Another object is to utilize a length of piano wire as a mandrel upon which to draw tubing 20 having a substantially capillary bore; a further object being to mount the wire with its end extending within a drawing die whereby a tube of relatively large diameter may be drawn through the die to reduce its diameter and simultaneously 25 drawn onto and over the wire mandrel to ensure uniformity and smoothness of bore in the drawn tube; a still further object being to harden and/or chromium plate the drawing tip of the wire opposite the die to thus improve the quality and 30 uniformity of the drawn product.

Among other objects is to provide an improved 35 easy and inexpensive method of producing uniformity and smoothness of the bore, particularly in capillary tubing; to provide an improved drawn tube of capillary bore; and to provide capillary tubing, especially of metal, having smooth uniform texture in the inner walls of the tube as well as having uniform cross-sectional area of 40 the bore throughout the length of the tube.

Numerous other objects, advantages, and inherent functions of the invention will be apparent 45 from the following description, which, taken in connection with the accompanying drawing, discloses a preferred embodiment of the invention.

45 Referring to the drawing:

Figure 1 is a schematic view showing apparatus for producing tubing in accordance with our invention; and

Figure 2 is an enlarged sectional view of the 50 drawing die and mandrel.

To illustrate our invention, we have shown in the drawing apparatus for the fabrication of tubing, more particularly metallic tubing having a capillary bore dimension, by drawing a relatively larger tube simultaneously over a mandrel

and through a suitable die whereby the finished tube has a smooth-surfaced bore of uniform, preferably circular, cross-sectional configuration throughout the length of the tubing.

Capillary tubing heretofore produced is characterized by considerable roughness in the surface of the bore and also by considerable variation in the cross-sectional area and shape of the bore. In fact, we are informed that it has not been possible, heretofore, to produce metallic tubing having a smooth capillary bore of uniform cross-sectional area and shape and we have observed that capillary tubing made in accordance with existing practice has considerable variation in the bore throughout its length and seldom, if ever, and then only accidentally, is of truly circular cross-sectional shape. In precision instruments, as, for instance, where capillary tubing is utilized to carry flowing fluids, or where the use of the tubing demands a known volume of fluid passing per unit of time through a given length of the tubing, for example, in the transmission of fluid under pressure from a temperature measuring device to a recording instrument, such variation makes it extremely difficult to 5 calibrate the precision instruments.

The rough unfinished bore surfaces in tubing of the sort provided heretofore is also a variant feature making the use of capillary tubing unusually laborious due to the necessity of accurately measuring and calibrating the flow characteristics of each individual length of tubing utilized. By producing tubing having bore uniformity, a standard product is achieved thus, eliminating much of the labor and disadvantages heretofore encountered in the calibration and use of capillary metallic tubing.

To this end, we propose to fabricate metallic tubing by drawing the same through an opening 9 in a die 11 in order to compact or squeeze 40 the tube material upon a sustaining pin or mandrel preferably comprising a length of piano wire 13 having an end 15 disposed within the die opening 9.

The die 11 is or may be firmly mounted, at a drawing station, in any suitable fashion and means 17 is provided for anchoring an end of the wire mandrel 13 in position such that its end 15 may extend within the die opening 19. The end 15 of the mandrel is preferably hardened and surfaced with a finishing coat 19, preferably comprising chromium, electrolytically or otherwise plated upon the end of the mandrel. The mandrel may be detached from its anchor 17 in order to permit the same to be threaded into 50 55

a length of tube stock 21 having inner and outer dimensions substantially larger than the inner and outer dimensions of the finished tubing after the drawing operation. The end of the stock tube 21 may be mechanically reduced, as at 23, to permit the end of the stock tube to be inserted through the opening 9 of the die and then flattened to permit the attachment of drawing tongs 25. The mandrel 13 is then connected to the anchor 17 and the stock tube drawn through the die by advancing the drawing tongs preferably under uniform tension in the direction of the arrow in Figure 1 of the drawing.

The opening 9 in the die 19 has its narrowest dimension nearer to the die surface facing away from the anchor 17, the leading edge of the opening being rounded as at 27. The trailing edge of the opening is also rounded as at 29, in order to form a conical depression 31 facing the incoming tube stock 21. As the tube stock 21 is drawn through the opening 9, the inclined surfaces of the conical depression 31 will exert a leverage upon the walls of the tube thus causing the material of the same to be drawn inwardly, as at 33, and compacted upon the hardened end 15 of the mandrel, which thus forms a sustaining element adapted to maintain and determine the shape and size of the bore in the finished product. As the tubing is thus drawn upon and over the mandrel, it simultaneously passes through the portion of minimum diameter in the die opening 9, which thus determines the outside diameter of the finished tubing. The hardened end of the mandrel extends through the die and projects a sufficient distance in front of the same to support the tube during and after its passage through the die. The extreme tip of the mandrel is also preferably rounded as clearly shown in Figure 2.

The drawn tube 35, as it leaves the extreme end of the mandrel, will have uniform smooth internal and external surfaces and the bore will be of a uniform size and cross-sectional shape, throughout the length of the tube, corresponding to the diameter and cross-sectional configuration of the mandrel. The texture of the bore surfaces in the finished tube 35 will be substantially smooth and we believe that the smooth texture of the bore surfaces is in part provided by the chromium plated finishing layer 19 on the mandrel at the place where the tubing is drawn onto and over the mandrel. We have discovered that tubing drawn on a chromium plated mandrel has unusual smoothness and uniformity in its bore surfaces.

While any suitable hard material may be used in forming the die 11, we prefer to make the die of tungsten carbide and to coat the surfaces of the drawing aperture with chromium since we find that this provides a superior finish in the outer surfaces of the drawn tube.

It will be noted that the wall thickness of the tubing is slightly reduced during passage of the stock tube through the die. In other words, there is sufficient material in the stock tube to ensure that the same, in passing through the die will be firmly pressed at all points in the circumference of the tubing upon the hardened surface of the mandrel, or sustaining member, thus ensuring a uniform cross-sectional area and size in the bore of the finished tubing as well as smoothness in wall texture in the bore. It should be also noted that the reduction in wall thickness of the tube, during the drawing operation, will result in an extension in tube length. At the conclusion of

the drawing operation, when all of the stock tube has passed through the die, it is simply necessary to sever the flattened end 23 along the line 37 and the tubing is ready for whatever use or service to which it may be desired to put the same. 5

It is thought that the invention and numerous of its attendant advantages will be understood from the foregoing description and it is obvious that numerous changes may be made in the form, construction, and arrangement of the several parts of the illustrated apparatus without departing from the spirit or scope of our invention or sacrificing any of its attendant advantages, the preferred modes and forms herein described being merely for the purpose of illustrating the invention. 15

Having thus described our invention, what we claim as new and desire to secure by Letters Patent is as follows:

1. A die for drawing tubes comprising a block 20 of tungsten carbide having an opening through which tubes may be drawn, the surfaces of said opening being coated with chromium.

2. Apparatus for drawing tubes comprising a die through which tubing may be drawn and a mandrel comprising a length of piano wire adapted to extend within the tubing as it passes through the die whereby to support the tubing internally, an end of said piano wire mandrel extending through the die and projecting therebeyond a distance greater than the diameter of the mandrel whereby to support the tube as and after it leaves the die. 30

3. Apparatus for drawing tubes comprising a die through which tubing may be drawn, and a mandrel adapted to extend within the tubing as it passes through the die whereby to support the tubing internally, said mandrel being adapted to extend through the die and to project therebeyond a distance greater than the diameter of the mandrel, whereby to support the tube as and after it leaves the die, wherein the mandrel comprises piano wire having a rounded end projecting beyond the die. 40

4. Apparatus for drawing tubes comprising a die through which tubing may be drawn, and a mandrel adapted to extend within the tubing as it passes through the die whereby to support the tubing internally, said mandrel being adapted to extend through the die and to project therebeyond a distance greater than the diameter of the mandrel, whereby to support the tube as and after it leaves the die, wherein the mandrel comprises piano wire having its end portions chromium plated and extending in and projecting beyond the die. 50

5. Apparatus for drawing tubes comprising a die through which tubing may be drawn, and a mandrel adapted to extend within the tubing as it passes through the die whereby to support the tubing internally, said mandrel being adapted to extend through the die and to project therebeyond a distance greater than the diameter of the mandrel, whereby to support the tube as and after it leaves the die, wherein the mandrel comprises piano wire having hardened end portions extending in and projecting beyond the die. 60

6. Apparatus for drawing tubes comprising a die of tungsten carbide having an opening 70 through which tubing may be drawn, and a mandrel comprising a length of piano wire adapted to extend within the tubing as it passes through the die whereby to support the tubing internally, said piano wire mandrel having an 75

end extending through the die and projecting therebeyond a distance greater than the diameter of the mandrel whereby to support the tube as and after it leaves the die.

5 7. Apparatus as set forth in claim 6, wherein the die as well as the portions of piano wire

mandrel extending therethrough have a plated coating of metallic material.
